UNITED STATES PATENT OFFICE.

CONRAD B. MANSBACH, OF BROCKTON, MASSACHUSETTS, ASSIGNOR OF ONE-HALF TO
FRANK L. PRICE, OF BROCKTON, MASSACHUSETTS.

COMPOSITE HEEL.

1,220,660.

Specification of Letters Patent. Patented Mar. 27, 1917.

Application filed November 20, 1916. Serial No. 132,305.

To all whom it may concern:

Be it known that I, CONRAD B. MANSBACH, a citizen of the United States, residing at Brockton, in the county of Plymouth and 5 State of Massachusetts, have invented new and useful Improvements in Composite Heels, of which the following is a specification.

This invention is embodied in a composite 10 heel comprising lift sections assembled to form a heel-shaped nail-receiving crib, portions of which are formed entirely by said sections while other portions are separated by crevices, and a filling occupying the space 15 bounded by the crib and also occupying said crevices, and adapted to harden from a plastic condition, said filling being applied when plastic.

The object of the invention is to provide 20 at a minimum expense a strong and durable heel adapted to be securely held by nails and utilizing waste pieces of leather for the nail-receiving crib, and an inexpensive mixture or composition, which may include 25 shredded or comminuted waste leather, for the filling.

Of the accompanying drawings forming a part of this specification,—

Figures 1, 2 and 3 are perspective views 30 illustrating successive steps in building the heel.

Fig. 4 is a plan view of the completed heel.

Fig. 5 is an edge view of the same.

Fig. 6 is a section on the line 6—6 of 35 Fig. 4.

Fig. 7 is a section on the line 7—7 of Fig. 4.

Figs. 8, 9, 10, 11 and 12 are perspective 40 views of lift members employed in building the heel.

The same reference characters indicate the same parts in all of the figures.

My improved heel is built by assembling 45 on a suitable bed, which is preferably a complete lift 12, Fig. 8, and may constitute the top lift of the heel, a plurality of relatively elongated lift members, which, in the preferred embodiment of the invention, include a plurality of side members 13, Figs. 9 and

50 10, a plurality of breast members 14, Fig. 11, and a plurality of rear end members 15, said members being arranged to form a heel-shaped crib. During the building operation, I apply a plastic filling 16 which occupies 55 and fills the space bounded by the crib. The

crib-forming members overlap and are in contact with each other at their end portions so that the members 13 and 14 form solid crib portions P, Fig. 5, at the front corners of the heel, while the members 13 60 and 15 form solid crib portions P' near the rear end of the heel. By solid portions, I mean portions made up entirely of lift members, the fact being that the lift members are separated from each other between the 65 solid portions by crevices which are also occupied and filled by the plastic filling, so that portions of the filling are visible on the sides, rear end, and breast of the heel.

The preferred procedure in building the 70 heel is as follows:

The lift 12 is placed in a heel-shaped mold, two members 14 and 15 are placed upon it, and a layer of the filling material is spread upon the lift 12 as shown by Fig. 1. Two 75 members 13 and another layer of filling material are then applied, as shown by Figs. 2 and 3. The first step is then repeated and so on until the heel is built to the desired height. 80

The filling 16 is preferably composed of a mixture of shredded leather and a suitable binder, the mixture being adapted to harden by drying. During the building operation, the overlapping portions of the lift members 85 are united by cement. The lift members are arranged to receive the nails which attach the heel to a boot or shoe, so that the nails are not liable to split or crack the filling material. 90

The relatively narrow lift members may be made from waste pieces of sole leather, although other suitable material may be employed. The filling, while constituting a considerable portion of the bulk of the heel, 95 is confined and protected by the crib formed by the lift members.

It is obvious that the lift 12 may be omitted in building the heel, the members 14 and 15 and the layer of filling material 100 shown by Fig. 1 being deposited directly on the bottom of the mold which constitutes the equivalent of the lift 12 as a bed.

I claim:—

1. A composite heel, comprising a heel-shaped nail-receiving crib composed of relatively narrow elongated lift members assembled to form solid crib portions and intermediate crib portions containing crevices, and a filling occupying the said crevices and 110

the space bounded by the crib, and adapted to harden from a plastic condition, said filling being applied when plastic.

2. A composite heel, comprising leather lift members assembled to form a heel-shaped nail-receiving crib, the end portions of said members being in overlapping contact and forming solid portions of the heel, while intermediate portions of the members are separated by crevices, and a filling occupying the said crevices and the space bounded by the crib and adapted to harden from a plastic condition, the said filling being applied when plastic.

15 3. A composite heel, comprising a heel-

shaped nail-receiving crib composed of relatively narrow elongated lift members assembled to form solid crib portions and intermediate crib portions containing crevices, a filling occupying the said crevices and the space bounded by the crib, and adapted to harden from a plastic condition, said filling being applied when plastic, and a continuous lift secured to one side of the heel and covering the portion of the filling which occupies the said space.

In testimony whereof I have affixed my signature.

CONRAD B. MANSBACH.
